WILLIAM J. DOYLE, OF CINCINNATI, OHIO, ASSIGNOR TO THE WILLIAMSON HEATER COMPANY, OF CINCINNATI, OHIO, A CORPORATION OF OHIO

SMOKE-CONSUMING DEVICE

Application filed October 1, 1927. Serial No. 223,443.

This invention relates to a smoke consuming device which is especially adapted in the herein disclosed embodiment to application to the feed door controlling a furnace fire box.

An object of the invention is to provide a device of the class referred to which is simple and comparatively inexpensive of manufacture and which is very efficient in 10 performance.

Another object is to provide a device for the purpose stated which is adapted to be applied not only to new furnace constructions but which may be added with great 15 facility and small expense to old installations.

These and other objects are attained by the means described herein and disclosed in the accompanying drawings, in which:

20 Fig. 1 is a fragmental elevation of a furnace structure, showing, in dotted lines, a device of the invention mounted on the rear of the feed door.

Fig. 2 is a view taken on line 2-2 of Fig. 25 1, part being broken away.

Fig. 3 is a view taken on line 3-3 of Fig. 1.

Fig. 4 is a side elevational view of a modified form of the device of the invention, 30 operatively mounted upon a furnace door.

Fig. 5 is a fragmental elevation of a regulating door and adjustment means therefor.

It is a widely recognized fact that smoke results from incomplete combustion of fuel 35 and is therefore objectionable not only as a nuisance but as an economic loss. Devices have been provided whereby smoke from a fire box is consumed by various agencies, and some of these have been successful only 40 in so far as they overcome a nuisance. Numerous heretofore devised smoke consuming apparatuses have been of a more expensive construction which has rendered their adaptation to domestic use almost prohibitive.

In the present invention there is provided an apparatus which may be supported directly upon the interior face of a furnace feed door and which swings into and out of 50 the furnace as the door is closed and opened.

Practically all feed doors for fire boxes of furnaces are provided with some manner of adjustable air port for the purpose of admitting air above the fire in the fire box. The chief disadvantage attending the usual 55 air port lies in the fact that if opened too widely a chilling of the interior of the furnace results therefrom.

In the present structure the usual feed door 10 is provided adjacent the top with 60 an opening 11 provided with a closure means 12 in order to partially or completely close the opening 11 if desired. As shown in the drawings the closure 12 takes the form of a hingedly mounted door closing 65 under the influence of gravity and adapted to be retained in a semi or completely open condition by means of a cord or chain 13, which in domestic installations may be actuated from the floor above.

The control for closure door 12 may also be of the type shown in Fig. 5, wherein a lug 120 on the feed door or frame co- 70 operates with a pivotally mounted and notched arm 130 which is carried by the door 12 to hold the latter in various open positions.

The tuyère structure is preferably a single casting comprising upper and lower flanges 14 and 15 and lateral flanges 16, the edges of which abut the inner face 17 of the door 80 closely adjacent the edges 18 of the door thereby providing a hollow chamber between the inner face of the door and the interior of the furnace. The body of the tuyère extends downwardly as at 19 substantially 85 in alignment with the edges 18 of the door and is then developed into a plurality of tapered hollow projections which are conveniently shaped somewhat after the fashion of truncated rectangular pyramids and extend inwardly toward the fire pot. The 90 projections are suitably rounded at the corners to facilitate casting of the tuyère member. Each of the projections 20 has a reduced elongated opening 21 at its innermost 95 end. As will be noted from an inspection of Fig. 3 the heat from the fire pot may rise between the projecting nozzles 20 so that the relatively large surface area of each of the nozzles of the tuyère may be quickly and 100

uniformly heated. A baffle or apron 22 depends from and forms a continuation of the body portion 19 and is secured in position by being drawn into abutment with a plurality of lugs 23 extending from the bases 24 of the nozzles 20 by means of a pair of stove bolts 25 extending through perforations 26 in said bases 24 and through perforations 27 in the baffle 22. Nuts 28 are used to draw and retain the parts rigidly in position. The apron or baffle 22 terminates at a point 29 above the bottom inner faces 30 of the nozzles thereby providing a relatively wide shallow vertical passage 31 which provides communication between the bottom of the nozzles and the air port 11.

The entire structure may be assembled and then secured upon the inner face of a furnace door by means of a pair of bolts 32 which extend through the body of the feed door and the body portion 19 of the tuyère.

A pair of uncontrolled relatively small perforations 111 are provided in the door 12 somewhat above the level of the lower edge 29 of the baffle.

From the foregoing it will be noted that the device is inexpensively manufactured of cast metal which requires no machining and which is very readily assembled on the job by inserting and tightening the four bolts 25 and 32.

The operation of the device is as follows: the installation is simple and readily understood. After the device is assembled, on a furnace door and fire started in the fire pot, the heat from the fire pot renders the nozzles 20 quite hot especially at the bottom walls 30 thereof. The draft in the fire box will draw a quantity of air through the elongated opening 11 dependent upon the amount of opening of the control door 12. This air travels downwardly through the wide shallow passage 31 and immediately becomes somewhat warmer. As the air now strikes the bottom interior faces 30 of the nozzles its temperature is increased and it expands within said nozzles before it passes through the openings 21. As the heated air passes through the openings 21 it is of nearly uniform temperature with the smoke and gases which it there encounters. In this way the smoke, or unconsumed fuel in a gaseous state becomes mixed with fresh oxygen from the outside without chilling the smoke, so that combustion of the gases from the fuel with the oxygen from the outside air takes place under most favorable conditions and the smoke is completely consumed and additional heat is generated in the combustion chamber of the furnace. The perforations 111 permit entry of a small volume of air at all times so as to eliminate the possibility of explosion of gases which may find their way into the nozzles when the opening 11 is completely shut off by the control door

12. Thus there is at all times a sufficient flow of air through the tuyère to prevent burning of the metal.

As shown in Fig. 4 the tuyère structure may take a somewhat simplified form where in the general structure is substantially like the device shown in Figs. 2 and 3 but in which a forward wall portion 33 is provided integral therewith for abutment with the inner face 170 of the furnace feed door. In this form the wall 33 has a snout-like projecting member 34 in which the air inlet port 110 is disposed. The mounting of the device is somewhat simplified since the feed door 100 needs be but cut out as at 35 to admit the snout-like projection 34 and one or two bolts such as 36 inserted through the door and tuyère to secure the parts together. The tuyère has the usual hollow projections 200 and an integral baffle 220 which provides the wide shallow air passage 310.

It will be understood that the perforate ends 21 of the nozzles 20 will terminate at the edge of the fire pot when the device is in an operative position in the furnace so that the heated air and oxygen is projected into the combustion chamber of the furnace.

The structure of the invention herein disclosed represents a comparatively inexpensive and efficient embodiment but the invention herein should be understood to be not restricted to the exact structural details shown as modifications thereof and alterations skilled in the art.

What is claimed is:—

1. In a device of the class described the combination with a furnace comprising a body having a fire box opening, a perforate feed door controlling said opening, a hollow tuyère secured to the door and having its edges in abutment with the inner face thereof, and having hollow nozzles of truncated rectangular pyramidal shape extending inwardly into the fire box, said nozzles having perforations in their innermost ends and baffle means disposed intermediate the opposite ends of the nozzle and the door whereby movement of air through the perforation in the door is directed downwardly over the bottom walls of the nozzles for heating prior to its exit through the perforation in the nozzles.

2. As a new article of manufacture a tuyère structure comprising an integral casting providing a plurality of straight walled funnel-like projections adapted for mounting on the inner face of a furnace fuel feed door and a single baffle member extending across the ends of said projections.

3. In a device of the class described the combination of a furnace fuel feed door arranged for the admission of air adjacent its top portion, a single tuyère casting secured on the inner face of the door and

providing a plurality of tapered nozzles extending side by side across the width of the door, the reduced ends of the nozzles being perforate and adapted to extend into a furnace fire box, a single baffle plate secured in spaced relation with the inside face of the said fuel feed door and providing a wide shallow air passage, said baffle extending across and closing the upper portions of the enlarged ends of the funnel-like projections and terminating in spaced relation to the bottom portion of the tuyère.

In testimony whereof, I have hereunto subscribed my name this 23d day of September, 1927.

WILLIAM J. DOYLE.
